SAW FILING AND SETTING DEVICE
Warren H. Kellogg, 109½ W. Filbert St.,
East Rochester, N.Y. 14445
Filed May 22, 1964, Ser. No. 369,364
12 Claims. (Cl. 76—63)

This invention relates to a novel filing and setting device for saws, especially but not exclusively, band saws.

The primary object of the invention is the provision of a more efficient, more easily used, and more compact device of the kind indicated, which is especially desirable for the filing and setting of band saws, without removal of the band saw blades from their mountings, by simply clamping the device on the tables of the band saws.

Another object of the invention is the provision of a simple, relatively inexpensive, and mechanically superior device of the character indicated above, which comprises a base assembly carrying a saw-advancing mechanism, and separate filing and setting assemblies which are interchangeably mountable on the base assembly.

Other important objects and advantageous features of the invention will be apparent from the following description and the accompanying drawings, wherein, for purposes of illustration only, a specific form of the invention is set forth in detail.

In the drawings:

FIGURE 1 is a top plan view of a device of the present invention, showing the saw filing assembly in place on the base assembly;

FIGURE 2 is a side elevation of FIGURE 1, showing the filing assembly in depressed inoperative position, in full lines, and in elevated operative position, in phantom lines;

FIGURE 3 is a vertical longitudinal section taken on the line 3—3 of FIGURE 1, showing the saw advancing mechanism in depressed position, in full lines, and in elevated saw-advancing position, in phantom lines;

FIGURE 4 is a vertical longitudinal section taken on the line 4—4 of FIGURE 1;

FIGURE 5 is a top plan view of the device, showing the saw setting assembly in place on the base assembly;

FIGURE 6 is a side elevation of FIGURE 5, partly broken and in section, showing the saw setting assembly in depressed inoperative position, in full lines, and in elevated operative position, in phantom lines;

FIGURE 7 is an enlarged fragmentary perspective schematic view, showing the saw tooth setting pin or die in relation to teeth of a saw;

FIGURE 8 is a fragmentary section, like FIGURE 6, showing another form of tooth setting pin or die, on a reduced scale;

FIGURE 9 is a top plan view of FIGURE 8; and

FIGURE 10 is an enlarged section taken on the line 10—10 of FIGURE 8.

Referring in detail to the drawings, and first to FIGURES 1 to 4 thereof, the illustrated device has a base assembly 10, which comprises a base composed of a pair of parallel spaced longitudinally elongated flat plates 12, which are fixed, at one end, to the undersides of the legs 14 of a reclining U-shaped block 16, having a cross member 18 preferably flush with the adjacent ends of the plates 12.

The legs 14 of the block 16 are formed, near their inner ends 20, with aligned transverse bores 22. An inwardly extending arcuate arm 24 is fixed to and rises from the cross member 18 of the block 16, and terminates, at its inward end, in an upstanding saw blade holder 26.

The blade holder 26 is preferably of rectangular cross section, having outer and inner sides 28 and 30, respectively, the upper part of the inner side 30 being outwardly

offset from the lower part thereof, as indicated at 32. A centered vertical saw blade receiving slot 34 opens to the inner side of the holder 26, and to its upper and lower ends. A pair of vertically spaced saw blade clamping screws 36 are threaded through a side of the holder 26 for adjustably clamping a saw blade 38 in the slot 34. A depth gauge thumb screw 40 is threaded through the outer side 28 of the holder 26 to engage the untoothed edge 42 of the blade 38, so that teeth 44 of the blade are held projecting beyond the inner side 30 of the holder, to the desired degree.

A saw advancing mechanism 46 comprises an elongated lever 48 which is pivoted intermediate its ends, as indicated at 50, on the working side of the arm 24, at a point spaced above the block 16. A handle, preferably in the form of a spherical knob 52, is provided on the outer end of the lever 48, and a short laterally inwardly extending arm 54 is provided on the inner end of the lever, and is spaced longitudinally inwardly from the block 16. The terminal end 56 of the arm 54 is substantially aligned with the saw holder slot 34.

A flat pawl 58 has a circular inner portion 60 which is centrally pivoted, as indicated at 62, on the terminal end 56 of the arm 54, and an outwardly tapering portion 64 which terminates in a point 66. The portion 64 is tangential to the portion 60, at the side of the portion 60 adjacent to the saw blade 38. A coil spring 68 is connected, as indicated at 70, at its lower end, to the inner edge of one of the plates 12 of the base assembly 10, and is eccentrically connected, as indicated at 72, at its upper end, to the lower part of the portion 60 of the pawl 58, under tension, whereby the pawl 58, is normally yieldably held in a vertical position, angling toward the teeth 44 of the saw blade 38, as shown in FIGURES 3 and 4.

As is also indicated in these figures, the handle knob 52 serves to counterweight the lever 48 downwardly, against the resistance of the spring 68, only to the extent that thereby the pawl 58 is maintained in contact with the saw teeth.

At opposite sides of the pivot 50 of the lever 48, the lever is traversed by vertical inner and outer stop screws 74 and 76, respectively, which are arranged to have stop engagements, at different times, with the upper surface of the adjacent block leg 14.

The inner stop screw 74 is adjustable for limiting the downward reach of the pawl 58, and the outer stop screw 76 is adjustable to limit the upward reach of the pawl 58, so that advance upwardly of the saw blade 38 can be limited to one tooth at a time, or two teeth, at a time. The stop screws 74 and 76 are also adjustable to accommodate the advancing mechanism 46 to saw teeth of different dimensions.

The illustrated filing assembly 78 comprises a reclining transversely elongated U-shaped carriage 80, composed of a cross member 82, and parallel arms 84, which are substantially longer than the width of the base assembly 10. Clamp blocks 86 are removably secured, as indicated at 88, upon the cross member 82, at its ends, and extend inwardly therefrom. The blocks 86 have V-shaped notches 90, in their undersides, which are adapted to receive a filing edge 92 of a triangular file 94, a side 96 of which bears upon the upper surfaces of the carriage arms 84.

The carriage arms 84 are formed, at their free ends with laterally inwardly extending bearings 98, formed with aligned bores 100, which receive a shaft 102, which is longer than the carriage 80. The shaft 102 is removable from the bores 100 and is adapted to be engaged endwise through the bores 22 of the block legs 14, and then through the bores 100, whereby the carriage is pivotally and slidably mounted on the base assembly 10,

with the carriage positioned at the inward side of the block 16, as shown in FIGURES 1 to 4.

The carriage 80 is adapted to be manually moved upwardly from a reclining inoperative position, as in FIGURE 3, to an elevated operative position, shown in FIGURE 4, wherein the cutting edge 92 and adjacent sides of the file 94, are engaged in the notch between two adjacent teeth 44 of the blade 38. The elevating of the carriage 80 is preferably done by means of the handle 104 of the file, and the file worked back and forth, in the notch, by means of the handle 104.

Upon completion of such a filing operation, the carriage 80 is retracted, and the lever 48 of the advancing mechanism 46 is depressed, against the resistance of the spring 68, so as to cause the pawl 58 to advance the saw blade upwardly, preparatory to another filing operation.

For a saw tooth setting operation, wherein two adjacent oppositely angled teeth 44 are set, in one operation, the stop screws 74 and 76 are adjusted so that depression of the lever 48 advances the blade 38 upwardly, two notches at a time.

For a setting operation, the carriage 80 is removed from the base assembly 10, and is replaced by a setting assembly 106, shown in FIGURES 5 to 7.

The setting assembly 106 comprises a U-shaped yoke or carriage 108 having a cross member 110, which is set at an upward and inward angle relative to parallel spaced legs 112. The legs 112 are formed, on their laterally inward sides, at the free ends thereof, with bearings 114 which are formed with aligned bores 116. A shaft 118 is slidably and removably engaged through the bores 116, and is adapted to be engaged through the bores 22 of the block legs 14, with the yoke 108 positioned at the inward side of the block 16, as shown in FIGURES 5 and 6. A handle rod 120 is fixed centrally to and extends inwardly from the cross member 110 of the yoke 108 and has a handle knob 122, on its free end, which is adapted to be used to elevate the yoke 108 to the operative position, shown in phantom lines in FIGURE 6, wherein a setting die 124 is applied to adjacent saw blade teeth 44.

The setting die 124, comprises, as shown in FIGURE 7, a preferably cylindrical block 126 which is suitably fixed to the canted upper surface 128 of the yoke cross member 110. The upper part of the die block 126 is formed with a pair of oppositely angled setting surfaces 130, which are severally related to adjacent, oppositely angled saw blade teeth 44, as indicated in FIGURE 7. When contacts of the setting surfaces 130 are made with the teeth, further forcible upward pressure exerted manually, by means of the handle knob 122 completes the setting of the teeth. Following tooth setting operations are done in the same way, with advancements of the saw blade two teeth, at a time, between operations.

The device is adapted to be used, in connection with a band saw, by clamping the base assembly 10, in any suitable manner upon the table of the band saw, with the band saw blade extending upwardly between the base plates 12, whereby removal of the blades from its mountings on the band saw is obviated, with accompanying savings in labor and time consumed otherwise in removing and replacing the blades.

It will also be understood that other types of saw blades can be filed and set by means of the device hereinabove described.

FIGURES 8 to 10 show another form of tooth setting pin or die 124a, which is devised to set only one tooth, at a time, and is reversible. This form is provided to be substituted for the die 124, of FIGURES 1 to 7, to enable the user of the device to become accustomed to the use and operation of the device.

The die or pin 124a comprises a mutilated cylindrical block 126a, which is set removably but non-rotatably

in a recess 127a, in the cross member 110. The part 123a of the die 124a which extends above the cross member is of mutilated pyramidal shape, and has only one active saw tooth engaging surface 129a, which, as shown in FIGURE 10, is set in from the adjacent side of the block 126a, and is disposed at a sharper angle, to the perpendicular, than the opposite surface 131a of the part 123a.

Although there have been shown and described preferred forms of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A device of the character described, comprising a horizontal base assembly comprising parallel spaced plates, a reclining U-shaped block having a cross member bridging the plates and legs extending above and fixed to said plates, an arm fixed to and rising from said cross member and having a horizontal portion spaced upwardly from said block, a vertical saw blade holder on and rising from said horizontal portion, said holder having a side remote from said block, said holder being formed with a vertical saw blade slot opening to said remote side and to the upper and lower ends of the holder, blade clamping means on the holder, a carriage pivoted on said block and positioned at the said remote side of the blade holder, said carriage being adapted to be moved upwardly from a retracted position toward said blade holder, and a saw tooth working member on the carriage.

2. A device according to claim 1, wherein said working member comprises a file.

3. A device according to claim 1, wherein said working member comprises a file, said carriage being mounted for movement crosswise of the base assembly and the file being fixed in place on the carriage.

4. A device according to claim 1, wherein said working member is a tooth setting die.

5. A device according to claim 1, wherein said working member is a tooth setting die having a pair of opposed and oppositely angled setting faces for separately engaging two adjacent saw teeth.

6. A device according to claim 1, wherein said working member comprises a file, said carriage being U-shaped and having a cross member and legs, said legs and the legs of the block of the base assembly being formed with aligned bores, a shaft removably engaged through said bores, said carriage legs being spaced from each other at a distance greater than the block, and the file being fixedly mounted on the cross member of the carriage.

7. A device according to claim 1, wherein said working member is a tooth setting die, said carriage being U-shaped and having a cross member and legs, said legs being engaged with the outer sides of the legs of the base assembly block, the latter legs and the legs of the carriage being formed with aligned bores, a shaft extending through said bores, and a tooth setting die fixed on the cross member.

8. A device of the character described, comprising a horizontal base assembly comprising parallel spaced plates, a reclining U-shaped block having a cross member bridging the plates and legs extending along and fixed to said plates, an arm fixed to and rising from said cross member and having a horizontal portion spaced upwardly from said block, a vertical saw blade holder on and rising from said horizontal portion, said holder having a side remote from said block, said holder being formed with a vertical saw blade slot opening to said remote side and to the upper and lower ends of the holder, blade clamping means on the holder, a carriage pivoted on said block and positioned at the said remote side of the blade holder, said carriage being adapted to be moved upwardly from a retracted position toward said blade holder, and

a saw tooth working member on the carriage, and saw blade advancing mechanism comprising a lever pivoted intermediate its ends on a leg of the block of the base assembly, said lever having a handle on the end thereof remote from the carriage and a lateral arm located between the legs of the carriage between the cross member of the carriage and the saw blade holder, a saw blade engaging pawl pivoted on the lateral arm and extending upwardly therefrom, and a spring stretched between one of the plates of the base assembly and a part of the pawl eccentric with respect to its pivotal axis.

9. A device of the character described, comprising a horizontal base assembly comprising parallel spaced plates, a reclining U-shaped block having a cross member bridging the plates and legs extending along and fixed to said plates, an arm fixed to and rising from said cross member and having a horizontal portion spaced upwardly from said block, a vertical saw blade holder on and rising from said horizontal portion, said holder having a side remote from said block, said holder being formed with a vertical saw blade slot opening to said remote side and to the upper and lower ends of the holder, blade clamping means on the holder, a carriage pivoted on said block and positioned at the said remote side of the blade holder, said carriage being adapted to be moved upwardly from a retracted position toward said blade holder, and a saw tooth working member on the carriage, and saw blade advancing mechanism comprising a lever pivoted intermediate its ends on a leg of the block of the base assembly, said lever having a handle on the end thereof remote from the carriage and a lateral arm located between the legs of the carriage between the cross member of the carriage and the blade holder, a saw blade engaging pawl pivoted on the lateral arm and extending upwardly therefrom, and a spring stretched between one of the plates of the base assembly and a part of the pawl eccentric with respect to its pivotal axis, said lever carrying stop screws at opposite sides of its pivotal axis adapted to engage the top of a leg of the block on the base assembly, at different times for limiting upward and downward travel of the pawl.

10. A device of the character described comprising a base assembly including a fixed block, a vertical saw blade holder disposed above and fixedly-supported from said block, said holder being formed with means for receiving a saw blade in upright position, clamping means on the holder for holding in fixed position a saw blade when received in upright position in said holder, a carriage longitudinally-spaced from and facing toward said

holder and pivotally-connected to said block for pivotal movement between a retracted position away and spaced from said blade holder and an operative position toward and contiguous to said blade holder, and a saw tooth working member on said carriage.

11. A device of the character described comprising a base assembly having a saw blade holder, saw blade advancing mechanism mounted on the base assembly, a carriage pivoted on the base assembly and adapted to be moved from a retracted position to an operative position adjacent to the blade holder, and a saw tooth working member on the carriage adapted to engage saw teeth in the operative position of the carriage, said member comprising a tooth setting die, said member being provided with an irregular cross section recess, said die being removably, non-rotatably and reversibly engaged in the recess, said die having a mutilated pyramidal portion extending above said member, said portion having a single saw tooth working side opposed to an unmnitized side of said portion, said single working side being disposed at a different angle from said opposed side.

12. A device of the character described comprising a base assembly having a saw blade holder, saw blade advancing mechanism mounted on the base assembly, a carriage pivoted on the base assembly and adapted to be moved from a retracted position to an operative position adjacent to the blade holder, and a saw tooth working member on the carriage adapted to engage saw teeth in the operative position of the carriage, said member comprising a tooth setting die, said member being provided with an irregular cross section recess, said die being removably, non-rotatably and reversibly engaged in the recess, said die having a mutilated pyramidal portion extending above said member, said portion having a single saw tooth working side opposed to an unmnitized side of said portion, said single working side being disposed at a different angle from said opposed side, said working side being laterally inset from the side of said portion remote from said opposed side.
